HAIRPIN

Filed Nov. 9, 1922

FIG. 1.

FIG. 2.

FIG. 5.

FIG. 6. FIG. 7. FIG. 8.

FIG. 9.

FIG. 10. BY Joseph J. O'Brien

INVENTOR.

UNITED STATES PATENT OFFICE.

JOSEPH J. O'BRIEN, OF SPRINGFIELD, MASSACHUSETTS.

HAIRPIN.

Application filed November 9, 1922. Serial No. 599,916.

To all whom it may concern:

Be it known that JOSEPH J. O'BRIEN, citizen of the United States of America, residing at Springfield, in the county of 5 Hampden and State of Massachusetts, has invented certain new and useful Improvements in Hairpins, of which the following is a specification.

This invention relates to improvements in 10 hair pins and the leading object of the invention is to provide a self-locking hair pin consisting of a single strand of wire bent upon itself to provide opposing legs and flexible connecting joint of substantially U-shaped formation, each of the legs having 15 cam surfaces formed therein and the whole hair pin being so designed that upon insertion in the hair the cam surfaces will, upon engaging in the hair bring the terminal points of the legs together so as to 20 lock the strand of hair that has been wedged between the legs of the hair pin, the entire hair pin being constructed without requiring any additional material over a standard 25 hair pin of U-shaped construction.

Other objects of the invention will appear in the description annexed hereto which is fully illustrated in the following drawings; in which:

30 Fig. 1 is a plan view of one form of the invention.

Fig. 2 is an edge view thereof.

Fig. 3 is a transverse sectional view taken on line 3, looking in the direction of the 35 arrow.

Fig. 4 is a plan view showing the jaws of the hair pin in locked position.

Fig. 5 is a plan view of a modified form.

Fig. 6 is a similar view of another modified form.

Fig. 7 is a plan view of still another modified form.

Fig. 8 is an edge view thereof.

Fig. 9 is a plan view of a fourth modified form.

Fig. 10 is an edge view thereof.

The standard hair pin is constructed with legs which diverge from the joint connecting the legs to each other and in some 50 cases these legs are corrugated so that the corrugations form internally facing bends in registration with each other, the bends of the legs of the hair pins merely serving to provide recesses into which the hair may fit and to offer greater resistance to the withdrawal of the hair pin. When this hair 55

pin is inserted in the hair the legs are spread apart and the hair forced between the corrugated portions of the legs and gripping action depends upon the resiliency or resistance offered by the joint of the hair pin to the pressure developed by the hair between the legs of the hair pin.

In my invention the action obtained with the ordinary hair pin is reversed, in that after initial insertion in the hair, the terminal portions or jaws of the legs of the hair pin are brought together by a wedging action developed by cam surfaces formed on the edge of the hair pin and the hair itself so that the hair is retained in a closed space formed between the legs of the hair pin, the hair functioning with the particular construction of the hair pin to lock itself in selected position.

Referring to the accompanying drawings, in Figs. 1 to 4, a hair pin is shown consisting of a single piece of wire A which is bent upon itself to provide opposing legs A¹ and A² and an integral connecting U-shaped joint A³. The leg A¹ is provided with an outwardly curved portion or cam A⁴ and the leg A² is provided with a similar outwardly curved cam forming portion A⁵, the two portions A⁴ and A⁵ being disposed in registration with each other and being located near the joint A³ and the terminal portion or jaws A⁶ and A⁷ of the hair pin. The leg A¹ is preferably formed with a corrugation A⁸ located between the cam A⁴ and the joint A³ and this corrugation A⁸ extends at right angles to the plane of the corrugation or cam A⁴. The leg A² is provided with a similar corrugation A⁹ which extends in an opposite direction to the cam A⁸ but at right angles to the plane of the cam A⁵. Each of the cam forming portions A⁴ and A⁵ extends outwardly of the terminal portion of its leg so that the maximum diameter of the hair pin at the greatest width between the cams A⁴ and A⁵ is preferably in excess of the maximum diameter of the hair pin at any other point taken across the legs A¹ and A².

When the jaws A⁶ and A⁷ are forced into the hair so as to bring the cam portions A⁴ and A⁵ into contacting engagement with the hair, the pressure of the hair upon this cam forming portion or the resistance of the hair to the cam forming portion will cause the legs A¹ and A² to move toward the other so that the terminal portions A¹

and A^2 and A^6 and A^7 will assume the position indicated in Fig. 4, thus providing a closed hair pin with the hair located between the legs of the hair pin against accidental withdrawal. The space between the cams A^4 and A^5 provides a pocket to receive the hair wedged between the legs of the hair pin and this tends to assist in locking the hair pin against endwise movement 10 in the hair.

In Fig. 5 I show a slightly modified form of the invention with corrugations B^1 and B^2 formed on the legs of the hair pin B . The legs of the hair pin are provided with 15 cam surfaces B^4 and B^5 .

The outwardly disposed cam forming portions A^4 and A^5 constitute the meeting points of differently inclined or sloping portions of the legs A^1 and A^2 . These cams are located nearer the bend A^3 than the opposite or open end of the hair pin, so that the two legs will function as levers, upon the bend as a common fulcrum, and the small movement produced by the action of the hair upon 20 the cams will produce a greater movement of the leg terminals toward each other. The forward side of each cam slopes toward the axis of the open end or throat of the hair pin at a smaller angle than the rearmost 25 side of said cam, which is disposed on a sharper angle so that resistance to withdrawal will be greater than resistance to insertion of the hair pin in the hair.

The portions of the legs from the tips of 30 the cams to their terminals thus form grades or inclined planes which distribute the load of insertion over a greater length and surface, while the rearmost sides of the cams form inclined planes or grades which offer 35 greater frictional resistance to the withdrawal of the hair pin, since the pressure per unit of length is greater on the shorter sides of the hair pin cams, owing to their sharper angles, than on the longer sides 40 thereof.

In Fig. 6 I show another modified form of the invention whereby the corrugations A^8 and A^9 are omitted and the cam surfaces C^1 and C^2 are provided on the legs of the 45 hair pin C .

In Figs. 7 and 8 I show another modified form of the invention whereby a hair pin D is provided with legs D^1 and D^2 with cam surfaces D^3 and D^4 formed therein. The 50 terminal portion of the legs D^1 is provided with a corrugation D^5 and the terminal portion of the leg D^2 is provided with a similar corrugation D^6 but extending in opposite directions, both the cams D^5 and D^6 being disposed on planes at right angles to the cams D^3 and D^4 . The corrugations of 55 the legs of the hair pin B are disposed in parallel lines so that they will have an interfitting action when the jaws are brought 60 together.

In the case of the corrugations of the hair pin A , identified by the reference letters A^8 and A^9 , and the corrugations of the hair pin D identified by the reference letters D^5 and D^6 no resistance is developed by the 70 pressure of the hair opposing the action of the cams of the hair pin, such cams serving to lock the hair pin in its elected position in the hair and to not interfere with nor modify the movement of the legs toward 75 each other.

In order to provide for increased flexibility of the joint connecting the two legs of the hair pin, the joint portion of the hair pin may be corrugated in a plane at right 80 angles to the axis of the hair pin as indicated in Fig. 3. In this case the corrugated end of the hair pin provides a slightly wider surface so that it would be easier for the finger of the user to insert the hair pin 85 in the hair.

In Figs. 9 and 10 I show a fourth modified form wherein the U-shaped hair pin E is provided with legs E' and E'' , each having an outset cam forming portion E^2 located midway of the ends of the hair pin. Each cam forming portion or bend in each leg has a forwardly inclined portion E^3 and a rearwardly inclined portion E^4 , the former inclined portion E^3 being disposed at a 90 smaller angle to the axis of the hair pin than the inclined portion E^4 so that less resistance will be offered by the cams to the insertion of the hair pin and to the withdrawal of the hair pin. The opposing portions of the legs E' and E'' between the cams E^2 and the bend E^5 are shown to be 100 parallel but they may converge toward each other or diverge from each other. The portions of the legs which extend endwise of the cams E^2 are shown to have corrugations E^6 which are disposed at right angles to the direction of the cams E^2 so that the distance between the legs is not reduced or varied by said corrugations or the cams do not 105 neutralize nor modify the closing and opening action of the cams. The cams are disposed slightly inwardly of the terminals of the legs, thus locking substantially parallel 110 terminal portions of the hair pin. This construction permits of the manufacture of hair pins which differ but slightly from the standard hair pin but which embodies the self closing motion.

Having described my invention I claim: 115

1. A hair pin consisting of a U-shaped body providing opposing legs spaced apart from each other, the legs being provided with terminal portions forming hair entering points, said terminals being spaced apart 120 from each other a less distance than the portions of the legs near the longitudinal center thereof, and said portions being disposed outwardly of the planes of the terminals to provide leg propelling cam surfaces, the 125

said outwardly disposed portions having sloping surfaces and being capable of moving the terminals into contiguous relation when the hair pin is inserted in the hair, 5 but not into cross-wise relation.

2. A hair pin consisting of a U-shaped body providing opposing legs relatively movable toward each other and a connecting bend portion, a portion of each leg between

10 the bend and its terminal being disposed outwardly of the plane of the terminal portion to form a cam surface on its outer side and a hair pocket on its inner side, said portions having a width greater than the maximum width of the hair pin at any other

15 point thereon, said cam surfaces being offset to a depth and located from the bend and the leg terminals a distance sufficient to produce a self closing movement on the terminal portions of the leg to bring them into contiguous but not crossing relation.

3. A hair pin consisting of a U-shaped member providing a pair of relatively yieldable legs and a connecting bend, each leg

20 having an outset portion, the outset portion of one leg being in the same general plane as the outset portion of the other leg and each leg converging toward the other leg from its outset portion to the terminal of

25 said other leg, the terminal portions of the legs being spaced apart a less distance than the greatest distance between the outset portions, the legs converging toward the bend from said outset portions and each leg having a corrugated portion.

4. A hair pin consisting of a single piece of wire shaped to provide opposing sides and a connecting U-shaped bend, each of the sides being formed with an outward bend

30 presenting gradually sloping surfaces, the terminals of the sides being spaced apart

from each other to admit hair therebetween on the insertion of the hair pin in the hair, the said terminals being spaced inwardly of the planes of the outward bends and the 45 outward bends having outwardly disposed arches of depths sufficient to move the terminals of the sides into contiguous but not crossed relation when the hair pin is inserted in the hair upon the engagement of said 50 arches by the hair, said arches being spaced inwardly of the U-shaped bend and the distance between the sides of said U-shaped bend being substantially equal to the minimum distance between the sides forwardly 55 of said arches.

5. A hair pin formed of flexible material and bent upon itself to provide opposing legs relatively yieldable, each leg having an outwardly disposed cam forming surface lo-

60 cated between its terminal and the bend of the hair pin, the forward side of each cam being disposed on a lesser incline than the rearmost side thereof, the inclination of the rearmost side of each cam being the reverse 65

of the foremost side, whereby the resistance to insertion of the hair pin will be less than the resistance offered to withdrawal when the hair pin is disposed in human hair, the cam forming surfaces being offset a distance 70 sufficient to move the terminals of the hair pin legs into contiguous but not passing relation, the terminals of the legs being disposed inwardly of the planes of the outermost portions of the cam forming surfaces, 75 the sides of the hair pin converging forwardly and rearwardly of said cam forming surfaces and said surfaces being located nearer the bend of said hair pin than the terminals of the legs.

Signed by me at Springfield, Mass.
JOSEPH J. O'BRIEN.
